UNITED STATES PATENT OFFICE

148,199

DESIGN FOR A CHEST OF DRAWERS

William A. Tomlinson, High Point, and Rey W. Neville, Trinity, N. C., assignors to Tomlinson of High Point, High Point, N. C., a corporation of North Carolina

Application June 27, 1946, Serial No. 131,109

Term of patent 14 years

(Cl. D33—19)

To all whom it may concern:

Be it known that we, William A. Tomlinson and Rey W. Neville, citizens of the United States, residing respectively at High Point, in the county of Guilford and State of North Carolina, and Trinity, in the county of Randolph and State of North Carolina, have invented a new, original, and ornamental Design for a Chest of Drawers, of which the following is a specification, reference being had to the accompanying drawing, forming a part thereof, wherein—

Figure 1 is a perspective view of the chest of drawers embodying our new design;

Figure 2 is a front elevational view of the chest of drawers;

Figure 3 is a plan view of the chest of drawers;

Figure 4 is a side elevational view of the chest of drawers;

Figure 5 is an enlarged front elevational view of one of the pull members of the chest of drawers; and

Figure 6 is a plan view thereof.

We claim:

The ornamental design for a chest of drawers, substantially as shown.

WILLIAM A. TOMLINSON.
REY W. NEVILLE.
